UNITED STATES PATENT OFFICE.

FRED W. SMITH, OF RUTHERFORD, NEW JERSEY.

DESIGN FOR A TIRE.

• 54,694.

Specification for Design.

Patented Mar. 9, 1920.

Application filed November 15, 1919. Serial No. 338,390. Term of patent 14 years.

To all whom it may concern:

Be it known that I, FRED W. SMITH, a citizen of the United States, and a resident of Rutherford, in the county of Bergen and State of New Jersey, have invented a new, original, and ornamental Design for a Tire, of which the following is a specification, reference being had to the accompanying drawing, forming a part thereof.

The figure is a sectional perspective view of a portion of a tire showing my new design.

I claim:

The ornamental design for a tire, as shown.

FRED W. SMITH.
